AUTOMATIC CONTROL SYSTEM FOR
MOTION PICTURE MACHINES

William O'Neill, New York, N. Y.

Application February 21, 1931, Serial No. 517,429

8 Claims. (Cl. 88—16.2)

This invention relates to an automatic control system for motion picture machines, and has for its primary object and purpose to provide means operatively connected with one machine for automatically energizing the operating motor of a second machine at a predetermined point in the operation of the first machine so that the possibility of an hiatus or break in the continuity of the action of the scene or play being portrayed upon the screen will not occur by reason of error or inattention on the part of the operator. It is also a further object of my invention to provide a system of the above character applicable to such motion picture machines equipped with sound reproducing means and in which automatically acting means is employed to render the sound reproduction means of one machine inoperative and the sound reproduction means of a second machine operative in timed relation to the automatic energization of the operating motor of said second machine.

It is also an additional object of the invention to provide in such a system applied to three or more motion picture machines, means operable in case of emergency, as when one machine for any reason breaks down or becomes inoperative, which will enable the remaining machines to be automatically controlled and operated in the proper sequence.

With the above and other objects in view, the invention consists in the improved automatic control system for motion picture machines, and in the several novel features thereof, as will be hereinafter more fully described, illustrated in the accompanying drawings, and subsequently incorporated in the subjoined claims.

In the drawings, wherein I have illustrated several simple and practical applications of my present invention, and in which similar reference characters designate corresponding parts throughout the several views,—

Figure 1 diagrammatically illustrates my improved control system as applied for use in connection with the series of three motion picture machines, and

Fig. 2 diagrammatically illustrates the system as used in connection with two motion picture machines.

Referring in detail to the drawings, and more particularly to Fig. 1 thereof, 1, 2 and 3 respectively, indicate three individual motion picture projecting machines which may be suitably mounted and arranged in the conventional manner within the operator's room or station. In the illustrated application of my invention, each

of these machines is of the "talkie" motion picture type; or in other words, is equipped with means for the reproduction of the spoken words, music, etc., in synchronized relation with the actions of the characters in the scenic portrayal of the play upon the screen.

An individual electric drive motor 10, 20, 30 respectively, is provided for each of the picture projecting machines. With each of these machines, there is also associated two predetermined counters indicated at 5 and 6 respectively, having a common operating shaft driven from the shaft of the operating motor for the film reel of the projecting machine by a suitable driving connection as shown at 7. These counters 5 and 6 are of a well known type now on the market, and are provided with numeral bearing wheels which may be manually set, and also with movable circuit closing switch means indicated at 8 and 9 respectively, which is automatically operated when zero is displayed on the several numeral wheels to close an electric switch. Insofar as the purposes of the present explanation are concerned, further detail reference to these predetermined counters is not required.

Alternating or direct electric current is supplied for the operation of the motors 10, 20 and 30 from the 110 volt main lines 12 and 13 respectively. These main lines are connected by suitable conductors 14 and 15 with the spaced insulated blades of the movable switch means 8 operated by each of the predetermined counters 5, said switch blades being adapted to engage spaced contacts 16 which are connected by the conductors 17, 18 and 19 with the motors 10, 20 and 30 respectively. In each of these motor current supply circuits, there is interposed a double pole switch 10^a, 20^a and 30^a respectively. There is also provided a shunt circuit 21, 22 and 23 respectively, around each of the switch means 8—16, each of said shunt circuits having a double pole switch 10^a, 20^a, and 30^a, respectively, interposed therein.

The sound reproduction means of each projecting machine is connected by the wires 1^a, 2^a and 3^a respectively, with a pair of switch contacts 24, 25 and 26. In spaced relation to each of said pairs of contacts, the complementary contacts 24', 25' and 26' are arranged and connected by suitable wiring indicated at 27 to sound amplifiers (not shown). With the spaced pairs of contacts associated with each of the projecting machines, a movable switch member indicated at 24^a, 25^a, and 26^a respectively, is cooperatively arranged. Each of these movable switch mem-

bers is operated in one direction to open the circuit connecting the sound reproduction means with the amplifiers by a solenoid indicated at 31 and is moved in the opposite direction to close 5 said circuit by a second solenoid 32. With each pair of solenoids 31 and 32 the solenoids 33 and 34 are connected in parallel at one of their ends. The other ends of the solenoid coils 31, 32, 33 and 34 are connected by the wires 35 with the 10 main line current feed wire 13. In these conductors 35, the cut-out switches 10^b, 20^b and 30^b for the respective sound and dowser circuits are interposed.

The other side of the circuit for the solenoids 15 31, 32, 33 and 34 is through wire 35 connected with contact 9' and wire 36 which connects the movable switch member 9 with the current feed wire 12.

Solenoid 33 when energized, actuates the movable shutter or dowser of the picture projecting machine to its closed position while the solenoid 34 when energized, actuates said shutter to its open position.

In addition to the foregoing, certain emergency 25 circuits are provided. Thus, additional current supply wires 17', 18' and 19' are provided for the motors 10, 20 and 30 respectively. The switches 10', 20' and 30' are of the double throw type, and in normal operation, are engaged with the terminals of the main supply wires 17, 18 and 19. When thrown in the opposite direction, the switch 10' will close the circuit through wires 18', to motor 20, while the switch 20' will close the circuit through wires 19' to motor 30, and switch 35 30' will close the circuit through wires 17' to motor 10. The emergency circuits for the light shutters and sound reproducing means include a wire 40 connecting the solenoid 33 for machine #1 with solenoid 34 for machine #2 and wire 40 41 which connects solenoid 33 for machine #2 with the solenoid 34 for machine #3. These wires are connected with each other by wire 42 in which a switch 20^c is interposed. The solenoid 33 of machine #3 is also electrically connected 45 by the wiring 43 with the solenoids 34 of machines numbered 1 and 2, a switch 10^c being interposed in the circuit between the solenoid 33 of machine #3 and solenoid 34 of machine #2. The solenoid 34 of machine #1 is also connected by the conductor 44 with the solenoid 33 of machine #2 and has a switch 30^c interposed therein.

I also provide switches 10^d, 20^d and 30^d whereby the circuits for the sound control switches 55 and the light shutters of the respective machines may be operated independently of the counter-actuated switches 9.

When the control system is applied to only two projecting machines as illustrated in Fig. 2 60 of the drawings, the emergency circuits above referred to are of course, unnecessary. Otherwise, the arrangements of switches and the circuit wiring for such machines is the same as for machines numbered 1 and 2 in Fig. 1 of the drawings, and corresponding reference characters have therefore, been applied to the same parts in both diagrams. It will further be apparent that with only two machines to be operated, only a single cut-out switch 10^d is required in the sound and dowser or shutter control 70 circuit of projecting machine #1.

In preparing the projecting machines for operation, the operator first ascertains the exact 75 number of feet in each film reel from the starting position in the light aperture of the machine to

a predetermined distance from the end of the film, at which point the next projecting machine in the series is to be started in operation. Assuming as indicated in Fig. 1 of the drawings, that for the reel of machine #1 this distance is 784 feet, this number is set up manually on the numeral wheels of the predetermining counter 5 associated with the first projecting machine. There still remains a relatively short length of the film having images thereon, at the end of which the change over of the sound reproduction and the projection of the pictures or images is to be made from machine #1 to machine #2. Assuming that this additional length of the film is 10 feet, the operator will then set up the number 794 on the numeral wheels of the predetermining counter 6 associated with machine #1. This same procedure is observed with respect to the film reels for machines numbered 2 and 3, and the counters 5 and 6 associated with the latter machines are set accordingly.

Assuming that the several switches 10', 20' and 30' have all been thrown to the right and are in closed engagement with the terminals of the circuit wires 17, 18 and 19 respectively, the operator now closes switch 10^a and the cut-out switches 10^b and 20^b. The operating circuit for motor 10 is thus closed from the current supply lines 12 and 13 through the switches 10^a and 10' and conductors 17. In the operation of the projecting machine #1, counters 5 and 6 associated therewith are synchronously operated and when the numeral wheels of counter 5 have all been returned to zero, switch members 8 are automatically actuated to engage contacts 16 and close a circuit for the motor of projecting machine #2 from the line supply wires through wires 14 and 15, switch 20' and wires 18. This starts machine #2 in operation. The light shutter or dowser thereof however, is in closed position and the images will not be projected from said machine. When an additional 10 feet of film is run through machine #1 and the numeral wheels of counter 6 have all been returned to the zero position, switch member 9 is then automatically actuated and 110 engaged with contact 9' to close the circuit from the supply line 12 through conductor 35, solenoid coils 31 and 33, wire 35, cut-out switch 10^b and supply line 13. Simultaneously a circuit is closed through wire 40 and the solenoid coils 32 and 34 115 of the machine #2, conductor 35 connected therewith and cut-out switch 20^b to the supply line 13. Thus, it will be understood that by the energization of solenoid 31 of machine #1 and 32 of machine #2, the switch member 24^a of the first machine is moved to open position, thereby breaking the electrical connection between the sound reproduction means of said machine and the amplifiers, while switch member 25^a is moved to its closed position to engage contacts 25 and 25' and 120 close the circuit between the sound reproduction means of the second machine and the amplifiers through conductors 2^a and 27. Simultaneously, by closing the circuit of solenoid 33 associated 125 with the first machine and solenoid 34 associated with the second machine, the dowser or light shutter of the first machine is moved to closed position while the shutter of machine #2 is moved to its open position. Thus, the sound reproduction is automatically transferred and synchronized 130 with the projection of the picture images from machine #2.

After this transfer or change over is made from machine #1 to machine #2, the operator then opens switch 10^a, breaking the circuit of 135

motor 10 and discontinuing the operation of machine #1. The operator now re-threads projector #1 with the next reel of film to follow machine #2, or machine #3, if a series of three machines as shown in Fig. 1 are used. After this operation is completed, and before re-setting the predetermining counter 5 of machine #1, the operator must close switch 20^a so that the operating circuit for motor 20 of machine #2 will be maintained. If he fails to close this switch and re-sets the counter, the motor operating circuit would be broken at the switch contact 16. The predetermining counter 6 however, may be reset without first closing a switch.

15 When the film reel of machine #2 approaches its end, the same operations will take place as above described to automatically start the operation of machine #3 at the proper time and synchronize the projection of the pictures with 20 the sound reproduction, without any noticeable 25 break in the continuity of the action portrayed upon the screen.

In like manner, the counters 5 and 6 of machine #1 having been properly re-set, as the film 25 of machine #3 approaches its end, the automatic transference of the picture projection and sound reproduction will take place from machine #3 to machine #1. During operation of machine #3, cut-out switch 20^b is opened and switches 10^b and 30^b are closed.

30 By the provision of an automatic control system operating in the manner above described, it will be seen that plays of great length requiring three or more reels of film may be properly displayed without any break in the continuity of the action or interruption in the properly synchronized reproduction of the sound, and without requiring the attention or any action by the operator or attendant, insofar as the automatic 35 transference of such operations from one machine to another is concerned.

Assuming that projector #2 in Fig. 1 is in 40 operation and some part of this machine should break or for any other reason, its operation can- 45 not be continued, the third projecting machine may then be placed in operation in the following manner.

First, switch 20^a is opened, thus stopping the 45 operation of machine #2. The double throw 50 double-pole switch 20' is then thrown over to the left and connected with the terminals of wire 19'. Test switch 20^a is momentarily closed which will break the circuit of sound reproducing means for machine #2 and close the light 55 shutter or douser thereof, while the circuit for sound reproduction means of machine #3 is closed and the light shutter thereof moved to open position. Cut-out switch 20^b is then opened and switches 10^b and 30^b are closed. The emergency 60 switch 20^c is also closed. Upon now closing switch 20^a, operating current will be supplied 65 through wires 19' to motor 30, thus operating the projecting machine #3. Upon the exhaustion 70 of the film from this machine, the operations are automatically transferred to machine 75 #1, the operating circuit of motor 10 being closed through the switch contacts of the counter 5 associated with machine #3, and through switch 10' and wires 17. The sound and douser 80 circuits are closed through switch 20^c through wires 42 and 43 which connect the solenoids 31 and 33 of machine #3 with the solenoids 32 and 34 of machine #1. In a similar manner, it is possible 85 at any time, to cut out one machine in 90 the event of emergency from any connection

with the electrical control system, and continue the operation between the other two machines.

The predetermining counters 5 and 6 for automatically controlling the several circuits, directly operated by the motors of the picture projecting machines, enable my invention to be used in conjunction with such machines having self-contained sound reproducing means controlled by a sound track on the film, this type of talking motion picture machine being in almost universal use in preference to that type in which separate sound discs or records are used and operatively synchronized with the projection machine. Also this feature of my invention enables the same to be used to equal advantage in the projection of either silent or talking motion pictures.

From the foregoing description, considered in connection with the accompanying drawings, the relative arrangement of the several parts constituting my improved system of automatic control for a plurality of motion picture machines will be clearly understood. It will be evident that such a system will largely eliminate human error in the operation of such machines, or improper operation thereof, due to independent manual control and inattention on the part of the operator, which results in a break or hiatus between the termination of the picture projecting operation of one machine, and the beginning of such operation by a second machine. It will, of course, be understood that the various arrangements of switches and operating means therefor as indicated in the accompanying drawings are largely suggestive, and may be modified as circumstances or conditions might require. Also various equivalents for the predetermining counters 5 and 6 might be provided for the purpose of automatically opening and closing the necessary circuits in proper relation to the operation of the motion picture film.

It is therefore, to be understood that in the further commercial development of my present invention, I reserve the privilege of resorting to all such legitimate variations of the several novel 120 features of my improved system as herein disclosed, which may fairly be considered as within the spirit and scope of the invention as claimed.

I claim:

1. In combination with a plurality of motion 125 picture machines each having a single sound reproducing means and individual operating motors for said machines; an automatic control system including a current supply circuit for each motor, a normally open switch in each of said circuits, circuit connections between the sound reproducing means of each machine and sound amplifiers, a separate switch in each of said circuit connections, electrical means associated with and directly actuating each of the latter switches 130 to independently operate the same to open and closed positions, a control circuit for each of said switch operating means, a normally open switch in each of the latter circuits, and means associated with each machine and operatively 135 connected with the motor therefor independently of the sound reproducing means to actuate said normally open switch in the motor circuit of a second machine to closed position and to close said normally open switch in the sound reproduction control circuit of said second machine at a predetermined time in the operation of said first machine.

2. In combination with a plurality of motion 140 picture machines each having sound reproducing 145

means and individual operating motors for said machines; an automatic control system including a current supply circuit for each motor, a normally open switch in each of said circuits, circuit connections between the sound reproducing means of each machine and sound amplifiers, a switch in each of said circuit connections, electrical means associated with each of the latter switches to operate the same to open and closed positions, a movable shutter for the light aperture of each machine, electrical means for operating each shutter to open and closed positions, a common energizing circuit for the electrical switch and shutter operating means associated with each machine, a normally open switch in each of said circuits, and means associated with each machine and operatively connected with the motor therefor to actuate said normally open switch in the motor circuit of another of said machines to closed position and said normally open switch in the sound reproduction circuit of said first machine at a predetermined time in the operation of said first machine.

3. In combination with a plurality of motion picture machines each having sound reproducing means and individual operating motors for said machines; an automatic control system including a current supply circuit for each motor, a normally open switch in each of said circuits, circuit connections between the sound reproducing means of each machine and sound amplifiers, a switch in each of said circuit connections, electrical means associated with each of the latter switches to operate the same to open and closed positions, a circuit for each of said switch operating means, a normally open switch in each of the latter circuits, a pair of predetermined counters associated with each machine having a common driving connection with the operating motor therefor, said counters adapted to be set in accordance with the footage of the film reels in the respective machines, one of the counters in each pair actuating the open switch in the motor circuit of another of said machines to closed position, and the other of said counters actuating the open switch in the circuit of the operating means for the switch in the sound reproduction circuit of said machine to its closed position and in predetermined timed relation to the closing of the switch in said motor circuit.

4. In combination with a plurality of motion picture machines each having sound reproducing means and individual operating motors for said machines; an automatic control system including a current supply circuit for each motor, a normally open switch in each of said circuits, circuit connections between the sound reproducing means of each machine and sound amplifiers, a switch in each of said circuit connections, electrical means associated with each of the latter switches to operate the same to open and closed positions, a movable shutter for the light aperture of each machine, electrical means for operating each shutter to open and closed positions, a common energizing circuit for the electrical switch and shutter operating means associated with each machine, a normally open switch in each of said circuits, a pair of predetermined counters associated with each machine having a common driving connection with the operating motor therefor, said counters adapted to be set in accordance with the footage of the film reels in the respective machines, one of the counters in each pair actuating the open switch in the motor circuit of another of said machines to closed position, and the

other of said counters actuating the open switch in the circuit of the operating means for the switch in the sound reproduction circuit of the machine with which the latter counter is associated and the operating means for the light aperture shutter of said machine to their open and closed positions respectively and simultaneously energizing the switch and shutter operating means for said other machine to close the reproduction circuit thereof and move the shutter to open position.

5. In combination with a plurality of motion picture machines and individual operating motors therefor, an automatic control system including a current supply circuit for each motor, a normally open switch in each circuit, a device associated with each machine and operatively connected with the motor therefor to actuate the open switch in the motor circuit of one of the other machines to closed position at a predetermined time in the operation of said first machine, an additional emergency circuit for each motor, double throw switches for connecting the respective motors either in said first-named circuit or in the emergency circuit therefor, and an additional manually operable switch connected in each of the first-named motor circuits for closing said circuit independently of the normally open switch.

6. In combination with a plurality of motion picture machines and individual operating motors therefor, an automatic control system including a current supply circuit for each motor; a normally open switch in each circuit, a predetermined counter associated with each machine adapted to be set in accordance with the footage of the film reel for said machine and operatively connected with the motor therefor to actuate the open switch in the motor circuit of one of the other machines to closed position at a predetermined time in advance of the termination of the run of film of said first machine, an additional emergency circuit for each motor, double throw switches for connecting the respective motors either in said first-named circuit or in the emergency circuit therefor, and an additional manually operable switch connected in each of the first-named motor circuits for closing said circuit independently of the normally open switch.

7. In combination with a plurality of motion picture machines each having sound reproducing means and individual operating motors for said machines; an automatic control system including a current supply circuit for each motor, a normally open switch in each of said circuits, circuit connections between the sound reproducing means of each machine and sound amplifiers, a switch in each of said circuit connections, electrical means associated with each of the latter switches to operate the same to open and closed positions, a movable shutter for the light aperture of each machine, electrical means for operating each shutter to open and closed positions, a common energizing circuit for the electrical switch and shutter operating means associated with each machine, a normally open switch in each of said circuits, means associated with each machine and operatively connected with the motor therefor to actuate said normally open switch in the motor circuit of one of the other machines to closed position and said normally open switch in the sound reproduction circuit of said other machine at a predetermined time in the operation of said first machine, an additional

emergency circuit for each motor, double throw switches for connecting the respective motors either in said first-named circuit or in the emergency circuit therefor, an additional manually operable switch connected in each of the first-named motor circuits for closing said circuit independently of the normally open switch, and emergency circuits for the switch and light shutter operating means associated with each machine and a normally open switch in each of the latter emergency circuits.

8. In combination with a plurality of motion picture machines and individual operating motors therefor, each machine being provided with a light aperture shutter and having sound reproducing means associated therewith, means

operatively controlled by the motor for each machine independently of its sound reproducing means to energize the motor of a second machine at a predetermined time in advance of the termination of the run of film in said first machine, actuating means for the shutter of each machine, and additional means controlled by the motor of said first machine for energizing the shutter actuating means to move the shutter of the second machine to open position and for simultaneously rendering the sound reproducing means of the first machine inoperative and rendering the sound reproducing means of the second machine operative upon exhaustion of the film in said first machine.
